N. J. MERCER
CHILDREN'S FEEDING TRAY

Des. 162,860

Filed Oct. 21, 1946

FIG. 2.

FIG. 3.

INVENTOR

Norman J. Mercer

BY *John Price*

ATTORNEY

UNITED STATES PATENT OFFICE

162,860

CHILDREN'S FEEDING TRAY

Norman J. Mercer, Brooklyn, N. Y.

Application October 21, 1946, Serial No. 134,121

Term of patent 14 years

(Cl. D44—15)

To all whom it may concern:

Be it known that I, Norman J. Mercer, a citizen of the United States and residing at Brooklyn, in the county of Kings and State of New York, have invented a new, original, and ornamental Design for a Children's Feeding Tray, of which the following is a specification, reference being had to the accompanying drawings, forming part hereof and in which

Fig. 1 is a top perspective view of a children's feeding tray, showing my new design;

Fig. 2 is a top plan view; and

Fig. 3 is a front elevational view thereof.

I claim:

The ornamental design for a children's feeding tray, substantially as shown.

NORMAN J. MERCER.
